UNITED STATES PATENT OFFICE.

GEORGE E. WHEELER, OF CHAZY, NEW YORK.

COVER FOR EVAPORATING-PANS.

SPECIFICATION forming part of Letters Patent No. 393,196, dated November 20, 1888.

Application filed February 12, 1887. Serial No. 227,444. (No model.)

To all whom it may concern:

Be it known that I, GEORGE E. WHEELER, a citizen of the United States, residing at Chazy, in the county of Clinton and State of New York, have invented certain new and useful

5 Improvements in Covers for Evaporating-Pans, of which the following is a specification.

My invention relates to covers for evaporating-pans for use in the evaporation of fluids.

10 The main objects of my improvements are simplicity and cheapness of construction, and convenience and efficiency in use.

In the accompanying drawings, Figure 1 is a plan view of a cover which embodies my 15 improvements. Fig. 2 is a longitudinal vertical section of the same on line $x-x$ of Fig. 1. Fig. 3 is a transverse section of the same on line $y-y$ of Fig. 1. Fig. 4 is a view of a portion of the same on an enlarged scale; and Fig. 5 20 is a vertical section of a portion of my cover on line $z-z$ of Fig. 3, on the same scale as Fig. 4.

My cover is adapted for use with any ordinary shallow evaporating-pan having an open 25 top. The cover B is constructed so as to fit upon the open top of the particular form of pan employed. I prefer to make it with a longitudinal ridge and sloping sides, a form which might be termed "roof-shaped." The ridge or backbone a extends along through

30 the middle at the top, and a series of diaphragms or partitions, b , are secured to its underside. The outer ones of said diaphragms b serve as end pieces, and all of them are designed to extend downwardly to a point within 35 the pan below the fluid-line but not quite to the bottom of the pan when the cover is in place. The upper edges of these partitions b correspond in contour to the shape of the complete cover, as viewed in cross-section, and their lower edges

40 to the form of the pan. The two end partitions or diaphragms also serve to close, as it were, the gables of the cover, and they are set a distance from each other a little less than the length of the pan, so as to shut into the

45 pan at the ends. Longitudinal rods $c c$ extend through these partitions near the ends, the partitions being secured thereto, whereby the ridge a , partitions b , and rods $c c$ form a frame-work for the complete cover, the rods 50 $c c$ and ridge a forming the longitudinal connection of said frame. Doors d , on each side

of the ridge a and over each space or chamber between the partitions b , complete the cover. The ridge, however, is provided with an opening at the top of each chamber, over which I 55 place a draft-tube or chimney, f .

I form each door d of a frame-work, g , preferably of wood, extending around the edge of the door. Upon the under side of the frame-work I secure a sheet or coat of paper, h , or other equivalent non-conducting or insulating material, as, for instance, asbestos. The top and bottom of the frame-work is then covered with a thickness of sheet metal, leaving a dead-air space, k , within each frame-work and extending over the main portion of each door. The chimneys f are in the main metal tubes with a covering of non-conducting or insulating material, m , upon the outside. Each partition b is provided at the top edge with a lateral flange, n , which extends under the doors for a short distance at their confronting edges, thereby protecting the seam or crack between said edges. The under side of each door is also provided with a flange, o , to cover the 65 crack between the hinged edge of the door and the edge of the ridge-piece a . This flange, as shown in the drawings, is made integral with the sheet of metal that covers the bottom of the frame-work of each door; but it is immaterial 70 whether it is in one piece with said sheet or otherwise.

By constructing the cover with the partitions and compartment-doors, any chamber within the pan may be examined without in 75 the least disturbing the other compartments. By attaching the partitions to the cover instead of to the pan, they all can be removed 80 bodily with the cover and leave the entire pan free from all obstructions.

Another application, Serial No. 284,056, filed by me August 29, 1888, shows, but does not claim, some of the features herein shown, described, and claimed.

I claim as my invention—

1. The combination of the transverse partitions b , having the flanges n at their upper edges, with longitudinal connections for said partitions, and the doors d , the side edges of which doors close upon said flanges, substantially as described, and for the purpose specified.

2. The herein-described cover for an evaporating-pan having a series of connected partitions or diaphragms extending downwardly below its rim, and separate doors for the chambers between said partitions, substantially as described, and for the purpose specified.
3. An improved frame for the cover of an evaporating-pan, which consists of the ridge-piece *a*, partitions or diaphragms *b*, secured thereto, and the rods *c c*, combined substantially as described, and for the purpose specified.
4. An improved cover for an evaporator,

which consists of the ridge-piece *a*, the partitions *b*, the rods *c c*, doors *d*, and chimneys *f*, substantially as described, and for the purpose specified.

5. In an evaporator-cover, the ridge-piece *a*, the doors *d*, hinged thereto, and having the flange *o* to shut under the edge of said ridge-piece, substantially as described, and for the purpose specified.

GEORGE E. WHEELER.
